UNITED STATES PATENT OFFICE.

STANISLAW I. ROCLAWSKI, OF NEW YORK, N. Y.

CONDIMENT-HOLDER.

1,070,535.

Specification of Letters Patent. Patented Aug. 19, 1913.

Application filed September 7, 1911. Serial No. 648,078.

To all whom it may concern:

Be it known that I, STANISLAW I. Roc-
lawski, a citizen of the Russian Empire,
residing at New York, in the county of
5 New York and State of New York, have in-
vented certain new and useful Improve-
ments in Condiment-Holders, of which the
following is a specification.

My invention relates to improvements in
10 condiment holders and has for its leading
object the provision of an improved device
adapted to contain both salt and pepper or
pair of like commodities distributed from
shakers which will contain said commodi-
15 ties within a single holder and will permit
of the selective distribution thereof.

The further object of my invention is the
provision in a device of this character of
improved means whereby the shaking out
20 of the various commodities may be readily
and quickly controlled and either may be
cut out and locked against flow or distribu-
tion as desired.

Another object of the invention is to pro-
25 vide a device of this kind in which the mech-
anism for permitting and preventing the
egress of the contents will be so arranged
and disposed that it may be operated by the
simple act of grasping the device prelimi-
30 nary to its use.

Other objects and advantages of my im-
proved condiment holder will be readily ap-
parent by reference to the following de-
35 scription taken in connection with the ac-
companying drawings and it will be under-
stood that I may make any modifications in
the specific structure shown and described
within the scope of my claims without de-
40 parting from or exceeding the spirit of my
invention.

Figure 1 represents a side elevation of my
device. Fig. 2 represents a top plan view
thereof. Fig. 3 represents a sectional view
on the line 3—3 of Fig. 1. Fig. 4 repre-
45 sents a sectional view on the line 4—4 of
Fig. 2, and Fig. 5 represents a perspective
view of the sliding cut-off member.

In the drawings, the numerals 1 and 2 des-
50 ignate the two cylindrical portions of my
device each having the bore 3, said cylin-
ders 1 and 2 being connected by the short
web 4 which is of less height than the height
of the cylinders 1 and 2 which may be either
55 true cylinders or may taper upward
slightly. Said cylinders are adapted to con-
tain various pulverized substances such as

table salt in the cylinder 1 and pepper in
the cylinder 2, while engaged on the exte-
riorly threaded upper ends of the cylinders
are the threaded annular flanges 5 of the
60 perforate cap plates 6; said flanges 5 each
having a slot 7 formed in one side thereof.
In this construction, the salt and pepper
would ordinarily both be shaken out were
not some means provided to control the dis-
65 charge from the two cylinders. To control
this discharge, I form in the web 4 the
groove 8 which communicates at each end
with a vertical groove 9 formed in the in-
70 nner face of the adjacent cylinder, said groove
inclining or flaring outwardly, while fit-
ting into the groove 8 is the base portion 9'
of a rectangular bar 10 having a horizontal
portion and upstanding end portions adapt-
75 ed to fit in the groove 9 of one or the other
of the cylinders, the space between the end
portions being of less measurement than
the distance between the grooves, whereby
when one of the upstanding portions of the
80 bar fits entirely within one of the grooves 9
the other upstanding portion will project
from the face of the other cylinder. Said
upstanding portions each terminate in an
outwardly extending end 11 secured to the
85 under face of a perforate plate 12 having
its perforations so disposed as to be in aline-
ment with the perforations of the cap plate
6 when the bar portion bearing the plate is
disposed within the groove of the cylinder.

In the use of my device, I normally have
90 the two caps with their slots 7 disposed in
alinement with the grooves 9, whereby pres-
sure of the finger against the upstanding
portions of the bar 10 will slide the bar to
shift the plates into position where the open-
95 ings of one will correspond with the open-
ings of the cap thereabove while the open-
ings of the other will be out of alinement
with the openings of its cap and will pre-
vent discharge of material therethrough.

When it is desired to lock the slide in ad-
justed position it is merely necessary to push
the bar inward until its outer edge is within
a line circumscribing the cylinder at its
threaded portion and to then rotate the cap
105 plate until the slot thereof is out of aline-
ment with the groove 9 when the solid por-
tion of the flange 5 will secure the bar with-
in the groove.

From the foregoing description taken in
110 connection with the accompanying drawings
the construction of my improved condiment

holder will be readily understood, and it will be seen that I have provided a thoroughly simple and durable device of this character in which the discharge of the various condiments contained in the cylinders may be regulated as desired and in which either of the controlling plates may be locked to prevent discharge from the cylinder in which the said plate is disposed and 5 may be readily unlocked when desired and it will be also seen that the upstanding end portions of the bar are so disposed that they are in position to be engaged by the finger of the user in the simple and natural act of 10 using the holder so that it is only necessary to grasp whichever of the cylinders contains the condiment desired with the forefinger between the upper ends of the two cylinders, when the finger will engage the 15 upstanding end of the bar and will automatically open the desired cylinder and close the other one.

I claim:

1. A condiment holder comprising a pair 25 of containers and a connecting web extending therebetween, perforated caps for the containers, said containers extending above the web and having grooves formed in their mutually adjacent faces, members arranged 30 for movement into and out of the grooves, connections between the members for movement of each of the members out of its groove when the other member is moved into its groove, and plates connected with the 35 members and having perforations therein disposed for alinement with the perforations of the caps only when the members are in their grooves, said members being disposed for engagement by the finger of the user and 40 for movement thereby into their respective grooves individually when the holder is grasped for use.

2. A condiment holder comprising a pair 45 of containers and a connecting web extending therebetween, perforated caps for the containers, said containers extending above the web and having grooves formed in their mutually adjacent faces, members arranged for movement into and out of the grooves,

connections between the members for movement of each of the members out of its groove when the other member is moved into its groove, and plates connected with the members and having perforations therein disposed for alinement with the perforations 50 of the caps only when the members are in their grooves, said members being disposed for engagement by the finger of the user and for movement thereby into their respective grooves individually when the holder is 55 grasped for use, said caps being provided with flanges having slots normally registered with the grooves, said caps being rotatable to bring their flanges over the grooves and over the members therein. 60

3. A condiment holder comprising a pair of containers, a connecting web extending between the containers and terminating short of the upper ends thereof, said containers having grooves in their mutually adjacent faces, said web having a groove in its upper face communicating with the lower ends of the first-mentioned grooves, a bar having a bottom portion slidably engaged in the groove of the web and having outstanding end portions, adjusted for engagement in the groove of the adjacent containers, said end portions being so spaced that one of the end portions lies out of its groove when the other end portion is in its groove, said end 70 portions having laterally turned upper extremities projecting inwardly of the containers, perforated caps for the containers and plates carried by the laterally turned extremities of the bar and having perforations therein disposed for registration with the perforations of the caps only when the corresponding upstanding portion of the bar is in its groove, said upstanding portions when out of their grooves being exposed for 75 engagement and movement by the finger of the user. 80

In testimony whereof I affix my signature, in the presence of two witnesses.

STANISLAW I. ROCLAWSKI.
